UNITED STATES PATENT OFFICE.

JOHANN NADLER, OF VIENNA, AUSTRIA-HUNGARY.

LIFT OR ELEVATOR.

SPECIFICATION forming part of Letters Patent No. 440,111, dated November 4, 1890.

Application filed July 18, 1889. Serial No. 317,952. (No model.) Patented in Germany September 5, 1888, No. 48,185; in Belgium September 15, 1888, No. 83,165; in England September 19, 1888, No. 13,500; in Austria-Hungary October 1, 1888, No. 21,597 and No. 40,079, and October 3, 1889, No. 57,657 and No. 7,854, and in France October 23, 1888, No. 192,816.

To all whom it may concern:

Be it known that I, JOHANN NADLER, an engineer, subject of Austria, residing at 27 Lerchengasse, Vienna, in the Province of Nether-Austria, in the Empire of Austria-Hungary, have invented certain new and useful Improvements in Lifts or Elevators for Transporting Small Objects, (and on which I have obtained patents as follows: in Belgium, No. 83,165, dated September 15, 1888; in Germany, No. 48,185, dated September 5, 1888; in England, No. 13,500, dated September 19, 1888; in France, No. 192,816, dated October 23, 1888; in Austria-Hungary, No. 21,597 and No. 40,079, dated October 1, 1888, and No. 57,657 and No. 7,854, dated October 3, 1889;) and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The invention relates to improvements in lifts for elevating small objects—such as letters, newspapers, and the like—from the hall or lower door of a building to the stories above; and it consists in the construction and novel combination of parts hereinafter described, illustrated in the accompanying drawings, and pointed out in the appended claims.

In the drawings, Figure 1 represents a side elevation of the invention, the lower casing having its facing side removed to show the interior. Fig. 2 is a central vertical section of the same at right angles to Fig. 1. Fig. 3 is a partial side view of the lower casing, showing the operating crank. Fig. 4 is a plan view of the lower casing. Fig. 5 is a horizontal section of said casing. Figs. 6 and 7 are vertical sections of the upper part of the casing taken at right angles to each other. Fig. 8 is a detail view showing the arrangement of the brake-band.

Referring to the drawings by letter, *g* designates the casing of the actuating mechanism of the lift, which casing has on one side the vertical slot *g*² for the outward projection of the main shaft *w*, hereinafter described.

b b are vertical ways or directing grooves formed by or in strips secured to the inner surfaces of the casing *g* at opposite points, and *a* is a bearing-frame standing between the said strips and having upon it the outstanding strips *b'*, which project into the ways or grooves *b* and guide the frame *a* vertically as it moves up and down.

w w' are shafts journaled in the frame *a*, the upper main shaft *w* projecting through the slot *g*² and having attached the crank-handle *k*. Upon the shaft *w* is mounted a gear-wheel *r*, which meshes with a pinion *r'* on the shaft *w'*.

R is a pulley or rope wheel mounted on the shaft *w'*, and having a grooved periphery for the rope or cord passing over it. It has its periphery on one side of the groove flattened to receive a brake-band *f'*, hereinafter more fully described. *R'* is a similar pulley or rope wheel mounted on a shaft *w*², having suitable bearings at the top of the building, to which the lift is attached and covered in by a casing *g'*, having openings in its floor for the passage of the rope or cord *s*, that connects the wheels *R R'*.

The ends of the rope are connected by a sleeve-coupling *s'*, so that it may readily be placed and removed, and to said coupling are secured a hook and a chain to which light articles may be attached when desiring to raise the same. *q* is a buffer secured to the top of the coupling-piece *s'*, and preventing jar when the said coupling-piece strikes the floor of the casing *g'*.

t is a bag or basket shaped receptacle secured at *e* to a tube *h*, mounted and secured on the rope *s*.

d is an eye made in the upper part of the frame of the receptacle *t*, on the side opposite the tube *h*, and riding on the rope *s*.

The tube *h* has a projection *h'* upon it, which when the basket has descended far enough passes through a slot *i* in the top of the casing *g*, and strikes and depresses the outer arm of a lever *f*, pivoted upon the shaft *w*. To the end of the inner arm of the said lever is attached one end of a brake-band *f'*, which partly surrounds the wheel *R* and stops the motion of said wheel, and consequently

the descent of the basket, the other end of the band f' being attached to a fixed support within the casing.

The foregoing is a description of the elevator mechanism.

The following is a description of the indicator mechanism: Upon the top of the casing g , above a slot z^2 therein, is an indicator-scale z' covered, the front of the casing being 10 of transparent material—such as glass—by a suitable casing. Within the casing g , below the slot z^2 is secured the horizontal way l , upon which travels a block l' having a vertical pointer z , which faces the scale at one end 15 and can be moved successively to register with the vertical lines thereon, which lines are marked "1st story," "2nd story," and so on. A cord x having its upper end secured to one end of the block l' , passes over a pulley e secured in the casing g , to a proper support and divides into two strands, one of which passes under the pulley l' of a weight P , then over a pulley e^2 on the way l , and then to the shaft w . The other strand extends directly 20 to the shaft w , to which the adjoining ends of both strands are secured. A similar cord x' is secured to the opposite end of the block, passes over similar pulleys, has connected a similar weight, and has the ends of its strand 25 secured to the shaft w ; the ends of the strands of the cords $x x'$, being arranged to wind in opposite directions on the said shaft. It is evident that as the shaft w is rotated by means of the crank-handle k , one cord 30 will wind on and the other cord will unwind from the shaft and the block and pointer will be moved along the way l in front of the marks on the indicator, which marks are made at proper points to truly indicate the story to 35 which the basket or receptacle has risen.

The frame a has a short motion up and down, limited by the shaft w in the slot g^2 of the casing g . (See Fig. 2.)

The only function of the weights P is to 45 keep the cords $x x'$ sufficiently tense.

Having described my invention, I claim—

1. The combination, with the rope-wheels, the rope, and the tubes secured at a proper point to the rope and provided with a projection, of the lever pivoted on a shaft above the lower rope-wheel with its outer arm in the path of the said projection when the latter descends, and the brake-band attached at one end to the inner arm of the lever and

bearing on the lower rope-wheel, substantially as specified. 55

2. The combination, with the rope-wheels, the rope, the basket having an eye in its frame for the passage of the rope, and the tube attached to the rope and to the basket 60 at the side opposite said eye and provided with an instanding projection below the basket, of the lever pivoted within the casing and operated by said projection, and the brake-band attached to said lever and bearing on the lower rope-wheel, substantially as 65 specified.

3. The combination, with the casing having the slot g^2 and the vertical ways b within it, of the sliding frame having strips b' to 70 move in said ways, the shafts journaled in said frame, the upper shaft projecting through the slot g and having a crank-handle on its outer end, the gearing connecting the shafts, the upper and lower rope-wheels, the lower 75 rope-wheel being mounted on the lower shaft, and the rope connecting said wheels within the casing g , and the upper rope-wheel being mounted on a shaft near the top of the building, substantially as specified. 80

4. The combination, with the plate having the indicator-scale, the horizontal way therebelow, and the sliding block having a vertical pointer, of the shaft having a crank-handle, and the ropes or cords connecting opposite 85 ends of said block and the said shaft, passing over the necessary pulleys between the block and shaft and arranged to wind in opposite directions on the latter, substantially as specified. 90

5. The combination, with the plate having the indicator-scale, the horizontal way therebelow, and the sliding block having a vertical pointer, of the shaft having a crank-handle, the ropes having ends attached to opposite 95 ends of the sliding block, passing thence in opposite directions over pulleys, then each dividing into two strands, one of which runs direct to the shaft while the other passes over a pulley to its point of attachment to the 100 shaft and has a weight suspended to it between the two pulleys.

In testimony whereof I have affixed my signature in presence of two witnesses.

JOHANN NADLER.
